DESIGN FOR A RIBBON POCKET BELT

Dora Vertes, New York, N. Y., assignor to Heirloom Needlework Guild, Inc., New York, N. Y., a corporation of New York

Application March 16, 1943, Serial No. 109,767

Term of patent 3½ years

To all whom it may concern:

Be it known that I, Dora Vertes, a citizen of France and a resident of the city of New York, in the county of New York and State of New York, have invented a new, original, and ornamental Design for a Ribbon Pocket Belt, of which the following is a specification, reference being had to the accompanying drawing, forming part thereof.

In the drawing:

Fig. 1 is a perspective view of a ribbon pocket belt showing my new design.

Fig. 2 is a front view thereof with the flap of one of the pockets in opened position and with ends untied and unbuckled.

I claim:

The ornamental design for a ribbon pocket belt, substantially as shown.

DORA VERTES.
